ATOMIZER

Joy B. Schmitt and Fred Custer, Toledo, Ohio,
assignors to The DeVilbiss Company, Toledo,
Ohio, a corporation of Ohio

Application April 27, 1940, Serial No. 331,938

5 Claims. (Cl. 299—88)

The present invention relates to atomizers for spraying toilet liquids, medicinal preparations and the like. Those in general use employ compressed air from a hand operated rubber bulb to expel and atomize the liquid being applied. For traveling purposes it is desirable to have a closure on an atomizer to prevent leakage.

Because of the oily character of many of the liquids involved, considerable difficulty has been encountered in securing effective closing means. As the atomizers themselves are small the manual gripping area on the valves is limited. A strong spring that would hold the valve tightly against its seat might cause too much resistance for easy manipulation of the valve.

The comment is often heard that atomizers are unwieldy and awkward to put on a shelf or in a traveling case due to extended nozzles and dangling rubber bulbs.

One object of the invention is to produce an atomizer that is compact but at the same time having an elongated nozzle suitable for properly treating the mouth and throat. A further object is the provision of an effective closure that is easy to operate. An additional object is the provision of means for removing liquid from the liquid discharge passages after the atomizer has been used. A further object is the creation of an atomizer that is well balanced and attractive in appearance and convenient to use. Another important object of my invention is an atomizer that is inexpensive to manufacture and one that has few parts to get out of order. Other objects and advantages of the invention will be apparent during the course of the following description.

In the accompanying drawing forming a part of this specification and in which like numbers are employed to designate like parts throughout the same:

Figure 1 is a side elevation of an atomizer embodying our invention,

Figure 2 is a top plan view,

Figure 3 is a rear elevation,

Figure 4 is a sectional view of the upper portion of the atomizer taken on the line 4—4 of Figure 2, with a portion of the valve shown in full,

Figure 5 is a sectional view of the upper portion of the atomizer taken on the line 5—5 of Figure 4,

Figure 6 is a top plan view of the main body of the atomizer showing some of the internal passages in dotted lines, and with the parts arranged in operative position and,

Figure 7 is another top plan view of the main body of the atomizer with some of the internal passages shown in dotted lines and with the parts arranged in clean-out position.

The atomizer illustrated in the drawing comprises a bottle or similar receptacle 1 with a ferrule 2 cemented or otherwise securely fastened to the bottle neck. A main head piece 3 is threadedly connected to the ferrule 2, while a valve member 4 carrying a lead washer 5 is rotatably mounted on the main head piece 3. Air and liquid discharge tubes 6 and 7, respectively, project together from the valve member 4 and terminate in the spray tip 8. The liquid outlet tube 9 extends down into the bottle and is connected by means of nipple 10 to passage 11 in the lower part 12 of the valve member 4. When the atomizer is in the operative position the liquid flows from the passage 11 into annular passage 13, thru liquid passage 14 in the main head piece 3, and thence thru passage 15 in member 4 to the liquid discharge tube 7.

Air for operation of the atomizer is obtained thru manual compression of the bulb 16 whence air travels thru the nipple 17 into air passage 18 in main head piece 3 which connects with air passage 19 in valve member 4 which in turn communicates with air discharge tube 6.

A passage 20 in valve member 4 connects with a similar passage 21 in main head piece 3. The passages 20 and 21 act jointly as an atmospheric vent when the atomizer is in operative position.

A spring 22 and washer 23 yieldingly hold the valve member 4 against the main head piece 3. The spring 22 is compressed and exerts pressure against nipple 10 and the head piece 3.

When it is desired to use the atomizer the valve member 4 is manually turned by means of the nozzle so that the discharge tubes 6 and 7 are in the position shown in Figures 1 and 2. When the outlet tubes are so arranged the air passages from bulb 16 to the air tube 6 are open and the liquid passages from the bottle thru the outlet tube 9 are open to the liquid discharge tube 7.

On compression of the bulb air is discharged thru spray tip 8 and in passing therethrough draws liquid by suction from the bottle. This liquid is mixed with the air in spray tip 8 and is discharged therefrom in spray form. Atmospheric pressure is maintained within the bottle thru the vent passages 20 and 21.

After the atomizer is used and it is desired to put it away, the valve 4 is turned so that the tubes are in the clean-out position shown in

Figures 3 and 7 and in dotted lines in Figure 2. A marking such as "Clean out" as shown in Figure 3 may be used to indicate the point to which valve member 4 should be turned in respect to head piece 3. In this position the liquid passage 15 in valve member 4 communicates at its lower extremity with air passage 18 in main head piece 3. On compression of the bulb 16 air will be forced therefrom thru the air nipple 17 thru air passage 18 and thence into and thru the liquid passage 15, liquid tube 7 and spray tip 8. In this way is expelled any liquid left in the liquid passage 15, liquid tube 7, and spray tip 8 after the atomizer is used. This air cleaning of the liquid passages removes any liquid that might later drain therefrom to stain or otherwise injure the lining and other contents of the hand bag or other conveyance means.

Following this cleaning out operation the valve member 4 is turned further so that the discharge tubes are in closed position immediately above bulb 16. This position is shown in dotted lines in Figure 1. The air, liquid, and vent passages of the main head piece 3 are out of register with the corresponding passages in valve member 4 when the valve 4 is in this location. With the discharge tube so arranged above the bulb the atomizer is much more compact than when in operative position.

The soft lead washer 5 forming the contacting surface between valve member 4 and head piece 3 is held tightly against the head piece 3 by the force of spring 22. A tight seal is thus obtained. A spring of substantial strength may be used as considerable leverage to overcome the resistance caused by the spring tension is secured for turning the valve by moving it manually by means of the outer end portions of discharge tubes 6 and 7.

We wish it understood that our invention has been disclosed herein by way of example only and that numerous modifications and changes therein may be devised without departing from the inventive concept.

Having thus described our invention, what we claim to be new and desire to secure by U. S. Letters Patent, is:

1. In an atomizer, a liquid container, a head piece engaging the top of the container, air compression means depending from the head piece at one side of the container, a valve member rotatably mounted on the head piece to control the liquid passage from the container, and an elongated nozzle extending horizontally from the valve member, the valve member being closed when the nozzle is positioned above the air compression means and on the same side of the container, and being open when the nozzle is turned into position for use on the other side of the container.

2. In an atomizer, a container for the liquid to be sprayed, a head piece fastened to the top of the container, valve means mounted on the head piece for rotation on a vertical axis to open

and close the liquid container and an elongated nozzle extending radially from and rigidly connected to the valve means whereby the valve may be turned from open to closed position by manually swinging the nozzle in a horizontal arc.

3. An atomizer comprising a liquid container, a manually operated air supply means, a spray discharge orifice, a liquid passage from the container to the spray orifice, an air passage from the air supply means to the spray orifice, and a rotatable valve member intercepting the liquid and air passages and having corresponding passages, said valve having an open position in which the passages through the valve are in line with the liquid and air passages on both sides of the valve, a closed position in which the passages through the valve do not communicate with the passages on either side of the valve and a third position in which the portion of the air passage extending from the air supply to the valve communicates through a passage in the valve with the portion of the liquid passage extending from the valve to the spray orifice.

4. An atomizer comprising a liquid container, air supply means, a spray orifice, a liquid passage from the container to the spray orifice, an air passage from the air supply means to the spray orifice and valve means for temporarily by-passing air from the air passage into the liquid passage at a point between the liquid container and the spray orifice and thence through the outer section of the liquid passage to the spray orifice to remove from the passage any remnants of liquid left there after the atomizer has been used which might later cause damage by leaking from the spray orifice, said valve means for bypassing air into the liquid passage also serving to simultaneously close the outer section of the liquid passage from communication with the liquid container.

5. In an atomizer, a liquid container, a head piece with liquid and air passages therethru engaging the top of the container, an air compression bulb fastened to the head piece for supplying atomizing air to the air passage therein, a valve member with liquid and air passages rotatably mounted on the upper side of the head piece for controlling the flow of liquid from the liquid container and air from the air compression bulb, said member and head piece having flat contacting ported surfaces, a spray discharge nozzle extending from the valve member, a depending rod-like portion of the valve member passing down through a complementary bore in the head piece to serve as an axle member for the valve, a central liquid passage in the lower section of the rod-like portion communicating at its upper end with the liquid passage in the head piece, and a liquid outlet tube extending into the liquid container and connected to the lower end of the rod-like portion of the valve member and communicating with the liquid passage therein.
